(57) **CLAIM**

The ornamental design for transdermal patch container, as shown and described.

DESCRIPTION

FIG. 1 is a perspective view of the transdermal patch container as seen from the top, front and right sides.

FIG. 2 is a right side elevational view thereof, the left side elevation being a mirror image.

FIG. 3 is a top plan view thereof.

FIG. 4 is a front elevational view thereof.

FIG. 5 is a rear elevational view thereof.

FIG. 6 is a bottom plan view thereof.

FIG. 7 is a perspective view of the container of FIG. 1 shown in the open position and as seen from the top, front and right sides.

FIG. 8 is a right side elevational view of the container of FIG. 1 shown in the open position, the left side elevation being a mirror image.

FIG. 9 is a top plan view of the container of FIG. 1 shown in its open position.

FIG. 10 is a front elevational view of the container of FIG. 1 shown in its open position.

FIG. 11 is a rear elevational view of the container of FIG. 1 shown in its open position; and,

FIG. 12 is a bottom plan view of the container of FIG. 1 shown in its open position.
